UNITED STATES PATENT OFFICE.

FRANK FREDERICK LIPPOLDT, OF KINSLEY, KANSAS.

AUXILIARY AIR-INLET FOR ENGINES.

1,370,459.

Specification of Letters Patent.

Patented Mar. 1, 1921.

Application filed February 20, 1918. Serial No. 218,312.

To all whom it may concern:

Be it known that I, FRANK FREDERICK LIPPOLDT, a citizen of the United States, residing at Kinsley, in the county of Edwards and State of Kansas, have invented new and useful Improvements in Auxiliary Air-Inlets for Engines, of which the following is a specification.

This invention relates to vaporizers for internal combustion engines, the object in view being to produce a device capable of being combined and used in conjunction with the intake pipe or manifold of an internal combustion engine, whereby heated air is caused to commingle in a more effective manner with the explosive mixture on its way from the carburetor to the combustion space or spaces of the engine.

A further object of the invention is to produce a device of the character referred to which may be applied to internal combustion engines already in use, the operation of the device resulting in economy of fuel and greater efficiency in the engine, at the same time reducing the accumulation of carbon in the engine.

With the above and other objects in view, the invention consists in the novel construction, combination and arrangement of parts, as herein described, illustrated and claimed.

In the accompanying drawings,

Figure 1 is a side elevation of an internal combustion engine, illustrating the improved vaporizer in its applied relation thereto.

Fig. 2 is an enlarged sectional view through the valve and valve casing of the device, illustrating the internal construction thereof.

Fig. 3 is a fragmentary section showing the relation of the air inlet nozzle to the intake pipe of the engine.

Fig. 4 is a fragmentary section through the air heater.

The main feature of the present invention resides in the auxiliary air inlet valve and the manner of conducting heat thereto and emitting the heated air therefrom, within the intake connection of the engine.

To the above end, the device comprises a valve casing 1 at one end of which is a valve seat 2. Co-operating with the valve seat 2 is a check valve 3 shown in the form of a ball which is held yieldingly against the seat 2 by means of an expansion spring 4. One end of said spring bears against the

valve 3 and the other end normally bears against a screw plug 5 which is threaded into the opposite end of the casing 1. The plug 5 receives a stem or rod 6 which extends into the casing 1 and through the spring 4. The stem or rod 6 has a head 7 at the inner end thereof while a coiled spring 8 encircles said rod or stem 6, bearing at one end against the head 7 and bearing, at the opposite end against the plug 5. The stem 6 is slidable through a central opening in the plug 5, and has attached to its outer projecting end a controlling device 9, such as a rod or wire, which, in automobile practice, will extend through the dash where it will be provided with a suitable operating knob or handle, enabling the valve to be manipulated without the necessity of the driver dismounting from the machine. The stem 6, the spring 8, and the head 9 are all insertable through the spring 4 so that the head 7 will bear against the valve 3 and hold the same more firmly against its seat 2, the spring 8 being for that purpose made considerably stiffer than the spring 4. Extending off from the casing 1 at a point between the ends thereof, is an L-shaped nozzle 10 which is inserted through a hole in the intake connection 11 between the carburetor and the engine, the discharge end of the nozzle pointing downwardly as shown in Fig. 3 or in opposition to the normal flow or movement of the explosive mixture between the carburetor and the engine. This produces a more thorough condition of the explosive mixture and more thoroughly commingles the heated air therewith, the result being a more highly explosive mixture and one of increased combustibility.

The air admitted past the valve 3 is heated by means of a stove or heater 12 preferably of crescent-shape formation in cross section, and clamped upon the exhaust pipe of the engine by fastening means 13. A flexible conduit or pipe 14 extends in an upward direction from the heater 12 to the valved end of the casing 1, so that there is a natural tendency for the heated air to enter the casing 1 from which it is conducted into the intake pipe or manifold of the engine through the nozzle 10 which is perforated for that purpose.

In starting the engine when the latter is cold, the head 7 is permitted to bear with the full strength of the spring 8 against the valve 3. The valve 3 is thus held closed or

2
approximately so until the engine has started on a rich mixture. After the engine becomes heated, the operator withdraws to the necessary extent, the head 7 and thereafter only the comparatively light spring 4 resists the opening movement of the valve 3. This permits heated air to enter the intake pipe of the engine and freely commingle with, agitate and break up any globules of fuel which have not been vaporized by the carbureter. The result is economy of fuel and higher efficiency of the engine. At the same time, the rapid accumulation of carbon in the engine is retarded.

15 I claim:

An auxiliary air inlet for engines comprising an elongated tubular casing having at one end an air inlet and a valve seat surrounding the same, a plug closing the other

end of the casing and having a bore, said casing communicating intermediate its ends with the intake manifold of an engine, a stem slideable through the bore in said plug, a valve normally engaging said seat, a head carried by the stem and engaging said valve, a spring surrounding said stem and engaging said plug and said valve, a relatively stiff spring surrounding said stem and disposed within said first named spring in engagement with the head and the plug, and means for moving said stem whereby to compress the stiff spring and permit seating and unseating of the valve under the influence of the suction produced within the engine.

35 In testimony whereof I affix my signature.

FRANK FREDERICK LIPPOLDT.
